COMBINATION GAUGING TOOL.

1,408,085.

Specification of Letters Patent. Patented Feb. 28, 1922.

Application filed April 12, 1920. Serial No. 373,579.

To all whom it may concern:

Be it known that we, SKERRETT GARRATT, resident of 14 Bedford Street, GARRATT BARON, resident of 413 Lincoln Road, and ABRAHAM GARRATT, resident of 14 Bedford Street, all of Peterborough, in the county of Northamptonshire, England, and all subjects of the King of Great Britain and Ireland, have invented a certain new and useful Improvement 10 in Combination Gauging Tools, of which the following is a specification.

Our invention relates to a combination tool for use by engineers and others, the object of which is to provide a single tool, capable of use for a number of purposes, and at the same time of a compact and simple construction, capable of readily being carried in the owner's pocket.

Our improved combined tool may be used 20 as a T-square, ordinary square, angle gauge, curvature gauge, center line square, spirit level, depth gauge, plumb rule height gauge, surface gauge and width gauge.

According to our invention we employ a 25 suitable steel square, consisting of a thick steel base and a thin blade of steel or other suitable material secured to the base at about its centre and at right angles thereto. The base is provided with a slot, and in a recess 30 in this slot is provided a spirit level. Upon one side of the base its thickness is reduced by means of a V-shaped portion cut away so that the two inclined edges of the V are at 45° or other suitable angle to the edge of 35 the blade and so that the two sides intersect at a point on a continuation of the side edge of the blade, so that if the square be placed upon the end of a circular object so that the two sides of the V bear against the circumference 40 thereof, the edge of the blade will pass across the centre of the circular object. Thus by scribing lines against the edge of the blade in two or more positions, their intersection will locate the centre of the circular object.

A longitudinal slot is also provided in the blade of the square and this is preferably recessed upon the back to receive the head of a clamping screw which is located in the slot. 50 This clamping screw serves to secure a cross bar or blade also provided with a slot which engages over the clamping screw so that the cross bar may be slid over endwise or turned about the clamping screw so as to secure it 55 in position upon the blade of the square.

This cross bar is also provided with a transverse recess, adapted to engage over and fit closely upon the blade of the T square, so that when this recess is engaged upon the blade, the transverse bar will be secured at 60 right angles to the blade and parallel to the base. The bar may then be slid upon the blade of the T square and clamped in any desired position.

The clamping screw, for mounting the transverse bar upon the blade of the T square, comprises a hollow screw having a head adapted to fit in the recess in the back of the blade of the square, and a clamping nut, having a milled head, is adapted to engage upon it so as to clamp the transverse bar in position. A hole is provided right through the centre of the clamping screw and the outside thread is tapered at its end and split, so that by screwing a second milled 75 nut, having a tapered thread in its interior, on to the end of the hollow screw, the split portion will be contracted so as to clamp a scribe or thin bar passed through the aperture therein. Such a scribe comprises a thin 80 steel rod, bent at right angles at one end, preferably pointed and hardened so that when clamped in position it may be used for scribing lines upon an object, either on the vertical or horizontal face thereof.

A further small pointer, comprising a steel pin formed to a point at one end and engaged in a hollow steel screw, is provided in the slot in the transverse bar, and a clamping nut, having a milled head, is provided 90 on this screw so that the pointer may be secured in any desired position in the slot in the transverse bar.

When it is desired to carry the tool, in the pocket the transverse bar is turned parallel to the blade of the T square and clamped so as to lie thereon; the scribe is removed from the clamp screw in the blade, and the bent over end is inserted into a special hollow screw having a tapered split end and 100 adapted to be screwed into an aperture in the outer end of the transverse blade so that the scribe will be clamped in this screw by means of the bent over end, whilst the length of the scribe will lie parallel to and close 105 against the blade of the square.

The opposite end of the transverse bar is provided with a small square hole. To the top end of the blade of the T square may be secured a thin cord adapted to engage in a 110

slot therein and to be suspended over the edge of the blade so as to form a plumb line.

In order that our invention may be more readily understood reference is made to the accompanying sheet of illustrative drawings in which—

Fig. 1 is front elevation of our improved gauging tool.

Fig. 2 is a side elevation of the same.

Fig. 3 is a rear elevation of the tool.

Fig. 4 is a detail of the moveable cross-bar.

Fig. 5 is a detail of the clamp for the cross-bar, and

Fig. 6 is a detail of a moveable scribe 15 point.

Referring to the drawings, the T square comprises a base 1 from which projects the blade 2 at right angles thereto. The base 20 1 is provided with a slot 3, and a spirit level 4 is mounted therein, a hole 5 being drilled from one end of the base 1 for the reception of the spirit level 4 and plugged at the end by a screw plug 6.

25 In the back of the base 1 is provided a V shaped recess 7, the sides of which are inclined at an angle of 45° to the edge of the blade 2, and are arranged in such a position in the base 1 so that the two sides 30 intersect at a point on a continuation of one side edge of the blade 2, so that if the square be placed upon the end of a circular object with the two sides of the recess 7 against the circumference, thereof, the blade 35 will pass across the centre of the circular object thus enabling the centre to be marked by scribing a series of lines at an angle to each other.

40 A longitudinal slot 8 is provided in the blade 2 of the square, and this is recessed at 9 in the back of the blade to receive the head 10 of a clamping screw 11, by means of which a cross blade 12 may be clamped upon the blade 2. The cross blade 45 12 is slotted at 13 and the clamping screw 11 passes through the slot 13 in the blade 12 the slot 8 in the blade 2, the head 10 of this clamping screw engaging in the recess 9 in the back of the blade 2. A washer 50 14 is provided on the screw against the face of the blade 12, and a knurled nut 15 is screwed upon the clamping screw 11 so as to press upon the washer 14 and clamp the moveable blade 12 upon the T square blade 2.

55 The moveable blade 12 is provided with a recess 16 at about its centre, which recess is exactly at right angles to the length of the blade 12 and of such a width as to fit closely over the edges of the T square blade 2, so that when this recess 16 is engaged over the edges of the T square blade 2, the cross blade 12 will be maintained at right angles to the blade 2 and parallel to the base 1 of the T square. The blade 12 may 60 thus be slidden upon the blade 2, whilst be-

ing maintained parallel to the base 1 so as to act as a gauge for measurements of length.

The cross blade 12 is provided with a square hole 17 at one end, which is adapted to be engaged over the clamping screw 11 70 when it is desired to secure the cross blade 12 at its extreme end to the blade 2. At the opposite end of the blade 12 is provided a hollow tapered screw 18, having a knurled head 19 and which engages in a hole in 75 the end of the blade 12. This screw 18 is split longitudinally so that when it is screwed into the blade 12, the hole 20 through the axis of the screw 18 will be reduced so as to clamp a scribe or small 80 rod in position therein.

In a suitable position toward one end of the blade 12 are scribed a series of inclined lines 21 at varying angles to the blade so that the blade may be set at varying angles 85 to the blade 2 of the T square in accordance with these lines.

The clamping screw 11 is provided with a hole 22 passing axially through its centre for the reception of a scribe or other rod 90 23. The end of the clamping screw 11 projects considerably beyond the nut 15, which clamps the cross blade 12 in position, and its end 24 is tapered and split at 25, and a knurled headed nut 26 engages on this 95 split tapered end 24 of the clamping screw 11 so as to cause it to contract upon and hold the scribe 23 in position therein.

Adjustably mounted in the slot 13 of the cross blade 12 is provided the small clamping screw 27, upon which is provided the washer 28 and knurled headed nut 29 by means of which it may be clamped in any desired position along the length of the slot 100 13 in the blade 12. This screw 27 is provided with an axial hole passing through its centre, and a short scribe or pointed rod 105 30 is secured therein.

When it is desired to carry the tool in the pocket the cross blade 12 is turned parallel 110 to the blade 2 of the T square and clamped so as to lie thereon. The scribe 23 is removed from the clamping screw 11 in the blade, and the bent over end 31 of this scribe is inserted into the hollow, tapered 115 screw 18, which is then screwed into the blade 12 so as to clamp the scribe 23 in position so that its length lies parallel to and over the cross blade 12 and the T square blade 2. In this manner the parts may be 120 arranged so as to occupy a minimum of space, and to offer the fewest possible projections so as to enable the tool to be readily carried in a pocket or case.

What we claim as our invention, and desire 125 to obtain by Letters Patent is:—

1. In a gauging tool, the combination of a T square having a base and a blade at right angles thereto, said blade having a longitudinal slot, a slotted cross blade mounted 130

on the T square blade and means for adjustably clamping it thereon and a scribe held in said means, and disposed perpendicularly to the plane of the tool and passing through the slots in the T square blade and cross blade.

2. In a gauging tool, the combination of a T square having a base and a blade at right angles thereto, said blade having a longitudinal slot and a slotted cross blade mounted on the T square blade and means for adjustably clamping it thereon, a scribe held in said means on the cross blade, and the T square base having a V-shaped recess in one of the sides arranged so that the angle of the V will be bisected by a line drawn along one edge of the T square blade, which will pass through the intersection of its sides.

3. In a gauging tool the combination of 20 a T square having a base and a blade at right angles thereto, said blade having a recessed longitudinal slot, a slotted cross blade mounted on a hollow clamping screw, passing through the slots in the two blades, 25 a washer and clamping nut on the screw to clamp the blades together, a scribe mounted in the hollow clamping screw, said screw having a split tapered end, a nut on this tapered end to clamp the scribe therein, 30 and a V shaped recess in one side of the T square base arranged so that the angle of the V will be bisected by a line drawn along one edge of the T square blade, which will pass through the intersection of its sides.

4. In a gauging tool, the combination of a T square having a base and a blade at right angles thereto, said blade having a longitudinal slot, a slotted cross blade mounted 40 on the T square blade and means for adjustably clamping it thereon, a scribe held in an adjustable clamp on the cross blade, said cross blade having a hole in one end by which it may be mounted on the T square 45 blade, a split, tapered screw having a hole through its centre, screwed into the other end of this blade and adapted to hold the scribe when the tool is not in use.

5. In a gauging tool, the combination of 50 a T square having a base and a blade at right angles thereto, said blade having a recessed longitudinal slot, a slotted cross blade mounted on a hollow clamping screw passing through the slots in the two blades, a 55 washer and hollow clamping nut on the screw to clamp the blades together, a scribe mounted in the hollow clamping screw, said screw having a split, tapered end, a nut on this tapered end to clamp the scribe there- 60 in, said cross blade having a hole in one end by which it may be mounted on the T square blade, a split, tapered screw having a hole through its centre, screwed into the other end of this blade and adapted to hold the 65 scribe when the tool is not in use.

6. In a gauging tool, the combination of a T square having a base and a blade at right angles thereto, said blade having a longitudinal slot, a slotted cross blade mounted on the T square blade and means for adjustably clamping it thereon, a scribe held in an adjustable clamp on the cross blade, a V shaped recess in one side of the T square base arranged so that the angle of the V will be bisected by a line drawn along one edge of the T square blade, which will pass through the intersection of its sides, said cross blade having a hole in one end by which it may be mounted on the T square blade, a split, tapered screw having a hole through its centre, screwed into the other end of this blade and adapted to hold the scribe when the tool is not in use.

7. In a gauging tool, the combination of a T square having a base and a blade at right angles thereto, said blade having a recessed longitudinal slot, a slotted cross blade mounted on a hollow clamping screw passing through the slots in the two blades, a washer and clamping nut on the screw to clamp the blades together, a scribe mounted in the hollow clamping screw, said screw having a split, tapered end, a nut on this tapered end to clamp the scribe therein, a V shaped recess in one side of the T square base arranged so that the angle of the V will be bisected by a line drawn along one edge of the T square blade, which will pass through the intersection of its sides, said cross blade having a hole in one end by which it may be mounted on the T square blade, a split, tapered screw having a hole through its centre, screwed into the other end of this blade and adapted to hold the scribe when the tool is not in use.

8. In a gauging tool, the combination of a T square having a base and a blade at right angles thereto, said blade having a longitudinal slot, a slotted cross blade mounted on the T square blade, and means for adjustably clamping it thereon, a scribe held in an adjustable clamp on the cross blade, said cross blade having a hole in one end by which it may be mounted on the T square blade, a split, tapered screw having a hole through its centre, screwed into the other end of this blade and adapted to hold the scribe when the tool is not in use, an adjustable scribe point mounted in the slot in the cross blade and provided with a clamp nut to secure it in position, the T square base having a hole drilled in one end, a spirit level inserted in this hole, the T square base having a slot through which the spirit level may be viewed and a plug in the end of the hole in which the spirit level is inserted.

9. In a gauging tool, the combination of a T square having a base and a blade at

right angles thereto, said blade having a recessed longitudinal slot, a slotted cross blade mounted on a hollow clamping screw passing through the slots in the two blades, 5 a washer and clamping nut on the screw to clamp the blades together, a scribe mounted in the hole in this screw, said screw having a split, tapered end, a nut on this tapered end to clamp the scribe therein- 10 in, one end of the cross blades having a hole by which it may be mounted on the T square blade, a split tapered screw having a hole through its centre, screwed into the other end of this blade adapted to hold 15 the scribe when the tool is not in use, an adjustable pointed rod mounted in the slot in the cross blade and provided with a clamp nut to secure it in position, one end of the T square base having a hole, a spirit 20 level inserted in this hole, the T square base having a slot through which the spirit level may be viewed and a plug in the end of the hole in which the spirit level is inserted.

25 10. In a gauging tool, the combination of a T square, having a base and a blade at right angles thereto, said blade having a longitudinal slot, a slotted cross blade mounted on the T square blade and means 30 for adjustably clamping it thereon, a scribe held in an adjustable clamp on the cross blade, a V shaped recess in one side of the T square base arranged so that the angle of the V will be bisected by a line drawn along one edge 35 along one edge of the T square blade, which will pass through the intersection of its sides, one end of the cross blade having a hole by which it may be mounted on the T square blade, a split tapered screw having 40 a hole through its centre, screwed onto the other end of this blade and adapted to hold the scribe when the tool is not in use, an adjustable scribe point mounted in the slot

in the cross blade and provided with a clamp nut to secure it in position, one end 45 of the T square base having a hole, a spirit level inserted in this hole, the T square base having a slot through which the spirit level may be viewed and a plug in the end of the hole in which the spirit level is 50 inserted.

11. In a gauging tool, the combination of a T square having a base and a blade at right angles thereto, said blade having a recessed longitudinal slot, a slotted cross 55 blade mounted on a hollow clamping screw passing through the slots in the two blades, a washer and clamping nut on the screw to clamp the blades together, a scribe mounted in the hole in this screw, said screw having a split, tapered end, a nut on this tapered end to clamp the scribe therein, a V shaped recess in one side of the T square base arranged so that the angle of the V will be bisected by a line drawn along one edge 60 of the T square blade, which will pass through the intersection of its sides, one end of the cross blade having a hole by which it may be mounted on the T square 65 blade, a split, tapered screw having a hole through its centre, screwed into the other end of this blade and adapted to hold the scribe when the tool is not in use, an adjustable scribe point mounted in the slot in the cross blade and provided with a clamp nut to secure it in position, one end of the T square base having a hole, a spirit 70 level inserted in this hole, the T square base having a slot through which the spirit level may be viewed, and a plug in the end 75 of the hole in which the spirit level is inserted.
